(57) **CLAIM**

The ornamental design for a vehicle grille as shown and described.

DESCRIPTION

FIG. 1 is a front view of a vehicle grille in a closed state with environment, showing our new design.

FIG. 2 is a top, right and front perspective view with environment.

FIG. 3 is front elevation view of a vehicle grille in a closed state;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and

FIG. 9 is a front perspective view thereof.

FIG. 10 is a front view of a vehicle grille in an open state with environment.

FIG. 11 is a top, right and front perspective view with environment.

FIG. 12 is a front elevation view of a vehicle grille in an open state;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is a front perspective view thereof.

The broken lines of evenly spaced dotted lines, in FIGS. 1, 2, 10 and 11 show the boundary between the claimed design and environment, and form no part of the claimed design.

(Continued)

The vehicle grille includes a transitional state of appearance. The transitional states of appearance sequentially change between the open and closed states as illustrated in the drawings. The process or period in which the different state of appearances changes do not form a part of the claimed design.

The broken lines in FIGS. 3-9 and 12-18 illustrate portions of the vehicle grille that form no part of the claimed design.
